UNITED STATES PATENT OFFICE.

WILSON JOHN CARROLL, OF DENVER, COLORADO, ASSIGNOR OF ONE-HALF TO NED A. ALTMAN, OF CRIPPLECREEK, COLORADO.

LOCK.

SPECIFICATION forming part of Letters Patent No. 766,665, dated August 2, 1904.

Application filed August 18, 1903. Serial No. 169,938. (No model.)

To all whom it may concern:

Be it known that I, WILSON JOHN CARROLL, a citizen of the United States, residing at Denver, in the county of Denver and State of Colorado, have invented a new and useful Lock, of which the following is a specification.

The present invention relates more particularly to permutation-padlocks; and the object thereof is to provide novel and simple mechanism which will securely hold the shackle in locked relation against the attempts of a person ignorant of the combination to open the same, said mechanism having visual and audible indicators, so that it may be operated in the darkness as well as in the light.

A further object is to provide an automatically-opening shackle and a simple arrangement of parts in connection therewith, whereby, even should the mechanism be properly disposed to release the shackle, said shackle will not open until operated on in a certain manner, thus concealing the fact to an unauthorized person that the shackle is practically unlocked.

A still further object is to provide mechanism the different coacting elements of which can be slightly changed, so that the various locks constructed in accordance with the present invention will have different combinations.

The preferred construction is illustrated in the accompanying drawings, wherein—

Figure 1 is a side elevation of a lock constructed in accordance with the present invention. Fig. 2 is a sectional view through the same, the rear side of the casing being removed. Fig. 3 is a similar view showing the loosely-journaled tumblers removed. Fig. 4 is a vertical transverse sectional view through the lock. Fig. 5 is a perspective view showing the tumblers disassociated. Fig. 6 is a vertical sectional view through one of the tumblers. Fig. 7 is a cross-sectional view through a portion of the lock, showing the relation of the cross-bar of the latch to the side walls of the casing. Fig. 8 is a detail view showing the shackle unlatched.

Similar reference-numerals indicate corre-

sponding parts in all the figures of the drawings.

In the embodiment illustrated a casing 10 is employed, which is of substantially the usual form and is provided with side plates or walls 11. A shackle 12 has one end pivoted, as shown at 13, within the upper portion of the casing, its other end being reduced to form a nib 14, constructed to pass through an opening 15, formed in the opposite corner of the casing. The pivoted end of the shackle is provided below the pivot with a notch 16, in which is engaged the looped portion 17 of a spring 18, formed of wire and coiled about the pivot 13, the free ends 19 of said spring bearing against the inner wall of the casing. This spring tends to throw the shackle to open position, as will be readily understood.

Below the opening 15 and extending across the casing is a post 20, upon which is pivoted a latch 21. This latch extends upwardly, and its free end is provided with a downwardly-inclined hook or bill 22, adapted to engage in a downwardly-inclined seat or opening 23, formed in the nib 14 of the shackle. As illustrated particularly in Fig. 7, the latch 21 is of less width than the space between the side walls 11 and is centrally disposed in said space. To prevent the lateral swinging movement of said latch, a cross-bar 24 is employed which is carried by an intermediate portion of the latch and extends across the space between the side walls, said cross-bar being preferably triangular in cross-section with one of its edges disposed in rear of the latch. The lower end of the latch is provided with a notch 25, in which is engaged the looped portion 26 of a spring 27, formed of wire and coiled about the post 20, the free ends of said spring bearing against the adjacent portion of the casing, and thus urging the latch rearwardly to throw the hook 22 out of the seat 23.

The front casing-wall 11 is provided with a centrally-disposed circular opening 28 and through the same is passed a spindle 29. A hub 30, carried by said spindle, fills the opening 28 and has its outer exposed face provided with an annular scale 31, which coacts with

an indicator-line 32, formed on the casing-wall, all of which is hereinafter more fully described. The spindle 29 has its rear end journaled in the rear casing-wall, while its front end is provided with an operating-knob 33. A tumbler-disk 34 is fixed to the spindle, being preferably an integral part of the same, said tumbler-disk being located within the casing in rear of the latch 21 and having a peripheral notch 35, adapted to receive the cross-bar 24. This tumbler is furthermore provided on its rear side with an annular flange 36, having a series of notches 37 in its outer edge, said series being located in a portion of the flange only. Other tumbler-disks, 38 and 39, are loosely journaled upon the spindle 29 in rear of the disk 34, said tumbler-disks 38 and 39 each having on one face an annular flange 40, the outer edges of which constitute bearing-surfaces. These disks are also provided with peripheral notches 41, which when alined with the notch 35 of the disk 34 permits the rearward movement of the cross-bar 24, and consequently the disengagement of the latch 25 from the shackle. The flange 36 and the flange 40 of the intermediate disk 38 serve as spacing devices for the tumblers. All of said tumblers are provided with coacting teeth or projections 42, preferably struck up from the 30 metal and located in intersecting paths of movement, said projections being preferably arranged inside the flanges.

A post 43 is located at one side of the tumbler mechanism and extends across the casing. 35 Coiled upon this post is a click-spring wire 44, one end 45 of which bears against the edge wall of the casing, the other end being formed into a nib 46, that bears against the peripheral edge of the flange 36 and engages 40 in the notches 37 to form an audible indicator for the mechanism. The lateral displacement of this click-spring is prevented by the adjacent tumbler. Brake-wires 47 are also coiled upon the post 43, said wires each having one 45 end 48 bearing against the adjacent portion of the casing-wall, the other end being looped, as shown at 49, about the flanges 40 and frictionally engaging the same to prevent movement of the loosely-journaled tumblers, except when the projections 42 are in engagement and the knob is being revolved.

It is believed that the operation of this lock will be clearly apparent to those skilled in the art. When the shackle is closed and held by 55 the latch and the notches of the tumblers are out of alinement, said shackle is locked and is so fastened until an operator, knowing the combination, by properly operating the knob 33 brings the notches into alinement with the 60 cross-bar of the latch. This operation may be accomplished by moving the knob a predetermined number of marks upon the indicator in opposite directions or by means of a predetermined number of clicks of the spring-nib 46, which can be clearly heard. When

the alinement of the notches with the cross-bar has been obtained, the shackle is still held by the latch because of the downward inclination of the hook 22 and seat 23. It therefore becomes necessary to press the shackle 70 inwardly, thus freeing the latch so that the same under the action of the spring 26 will move rearwardly into the notches. The shackle will thereupon fly to open position.

It will be apparent that this structure is 75 simple, is easily operated, and by changing the relation of the projections 42 locks may be constructed which are not duplicates in operation. While three tumblers are perhaps sufficient for ordinary purposes and are 80 not liable to be accidentally operated to obtain the release of the shackle, a greater or less number may of course be employed, if desired. The elements, moreover, can be easily and cheaply manufactured. The brakes 85 and click-springs are formed of wire and attached to a single post. They serve to hold the tumblers in fixed relation and against accidental movement. A further important 90 feature resides in the fact that even if by continued manipulation the tumblers are properly positioned the shackle will not be entirely released and opened, so that it will be even more difficult for an unauthorized person to actuate the lock.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by Letters Patent, is—

1. In a lock, the combination with a casing, of a shackle pivoted thereto and having a free end that fits within the casing, a latch pivoted within the casing beneath the free end of the shackle and having a detachable interlocking engagement therewith, tumblers located at one side of the latch and normally holding the same in interlocked relation with the shackle, a spring bearing against the latch to urge the same toward the tumblers, and a spring for urging the shackle to open position.

2. In a lock, the combination with a casing, of a shackle pivoted thereto and having a free end that fits within the same, said shackle being provided in its free end with a downwardly-inclined seat, a latch pivoted at its lower end within the casing beneath the free end of the shackle and having at its upper end an offset downwardly-inclined bill that detachably fits in the seat of the shackle, tumblers located at one side of the latch and normally holding the same in interlocked relation

with the shackle, a spring bearing against the latch to urge the same toward the tumblers, and a spring for urging the shackle to open position, said latter spring serving to hold the 5 shackle and latch interlocked against the action of the latch-spring.

- 3. In a lock, the combination with a casing, of a shackle pivoted thereto and having a free end that fits within the casing, a latch pivoted below the free end of the shackle, said latch and shackle having at their free ends downwardly-inclined shoulders that are movable into and out of coacting relation, tumblers co-acting with the shackle for maintaining the 5 shoulders in coacting relation, and a spring surrounding the pivot of the latch and bearing against said latch to urge the shoulder of the same out of engagement with the shoulder of the shackle.
- o 4. In a lock, the combination with a casing, of a shackle pivoted thereto, a latch for locking the shackle, a spindle journaled in the casing and having an exposed operating-knob, a tumbler-disk secured to the spindle and co- 5 acting with the latch, said disk having a notch in its periphery, and an outstanding bearing-flange provided with a plurality of notches, a post located at one side of the tumbler-disk,

a click-spring coiled upon the post and having a tooth that bears against the flange and is 30 movable into the notches, other tumbler-disks revolvably mounted on the spindle and having peripheral notches, said disks being also provided with outstanding bearing-flanges, and 35 brakes comprising spring-wires coiled upon said post and having looped portions that frictionally engage and partially embrace the flanges, said spring-wires each bearing at one end against the casing.

5. In a lock, the combination with a casing, 40 having spaced side walls, of a latch pivoted within the casing, said latch being of less width than the space between the side walls, a cross-bar carried by the latch and slidably engaging the inner faces of the side walls, and 45 rotatable tumblers mounted between the walls and having notches, which, when alined, receive the cross-bar to permit the movement of the latch.

In testimony that I claim the foregoing as 50 my own I have hereto affixed my signature in the presence of two witnesses.
